UNITED STATES PATENT OFFICE.

HEINRICH PERROT, OF CALW, GERMANY.

COMPASSES.

Application filed December 29, 1919. Serial No. 343,228.

To all whom it may concern:

Be it known that I, HEINRICH PERROT, a citizen of the German Republic, and resident of Calw, Wurttemberg, Germany, have 5 invented certain new and useful Improvements in Compasses, of which the following is a specification.

The present invention relates to instruments such as compasses, dividers, scribes, 10 and the like comprising two pivotally-connected legs or members; and its object, stated briefly, is the provision of improved means for retaining the legs or members of the instrument in adjusted position and, 15 when one of such legs is of two-part construction, for effecting a fine adjustment of the outer part relatively to the fixed inner part.

According to the invention, the enlarged 20 disk-shaped portions or heads of the compass members which are arranged face to face and through which the pivot pin passes in the usual manner, are conjointly formed with a wedge-shaped peripheral edge for co- 25 action with a presser piece having a complementary wedge-shaped edge; the arrangement being such that the pressure exerted upon the presser piece by an adjusting device will be transmitted to the two coacting 30 wedge surfaces, with the result that the compass members will be securely clamped in position.

The fine adjustment of the two-part member is effected, according to the invention, 35 by means of a micrometer screw which operatively engages with the movable part of said member and is pivotally carried by the fixed part thereof, so that it can be utilized first to shift the first-named part 40 into the required position and thereafter to lock itself in engagement with said part to prevent its accidental displacement.

An embodiment of the invention is illustrated in the accompanying drawing, in 45 which:

Figure 1 is a face view of a compass constructed in accordance with the invention;

Figs. 2 and 3 are part-sectional detail views at right angles to each other, showing 50 the clamping device, and

Figs. 4 and 5 are, respectively, a side elevation and a vertical sectional view of the fine-adjustment device.

Referring more particularly to the drawing, *a* and *b* designate the two main members or legs of the compass, and *c* the pivot

pin which passes through registering central openings in the disk-shaped enlargements or heads *h* at the upper ends of said legs, the two heads having their inner faces disposed 60 in abutting relation, as usual. The leg *a* is of one-piece construction, and terminates in a point *d*; but the leg *b* is made in two parts and comprises a movable part or arm *f* which is centrally pivoted as at *g* to the 65 lower end of the upper fixed part or leg proper *b*, the said arm *f* terminating at its lower end in a point *e*.

The improved clamping means or device whereby the compass members are retained 70 in adjusted position, comprises two co-acting companion parts, one of which consists of the two heads *h*, the other part being constituted by a presser piece *k* which is shifted toward or from the adjacent edge 75 of the heads by a screw *m* rotatably fitted in an internally threaded socket *l*. The latter is held in place by a guide *s* which is pushed over it and to which there is fixed a pair of fingers *t* suitably connected to the 80 members *a* and *b* and having a certain amount of play relative thereto. The confronting edges of the two companion parts *h* and *k* are provided with complementary wedge-shaped surfaces for direct coaction 85 with each other, one of such surfaces taking the form of a V-groove and the other of a V-shaped projection fitting therein. In the construction illustrated, the groove is formed conjointly in the edges of the two heads *h* 90 and is indicated at *i*; but it will be understood that it may be formed instead in the edge of the presser part *k*, in which case the edges of said heads will be beveled to conjointly form the V-projection. In the 95 present construction, the edge of the presser piece fits in the V-groove *i*—*i*, as shown; and the inward movement of said presser piece, produced by means of screw *m* will have the effect of binding the coacting wedge surfaces tightly together and, hence, of retaining the compass legs *a* and *b* in adjusted position.

The device for effecting fine adjustment of the movable arm *f* comprises a micrometer screw or worm *n* provided with an operating wheel or nut *r* and journaled in a pair of spaced bearing lugs *o*, formed on a plate or bracket which is pivotally secured to leg *b* by a removable screw *q*. The threaded 105 or toothed portion of the screw or worm meshes with the worm teeth *p* formed on the

upper end of arm *f*, so that rotation of said screw in one direction or the other will produce a rocking movement of said arm about its central pivot *g*. The end or edge of arm *f* is cut at an incline to form the worm teeth *p* which are thus made of half length so to speak, and are arranged in such a manner as to fit between the screw and the compass leg or member *b*, as will be understood from Fig. 5; this arrangement enabling the ready assembling of the parts and their disassembling when necessary. The pivotal mounting of the screw-carrying plate on the pin or screw *q* enables a slight rocking movement of said plate and a consequent rocking movement of screw *n*, which latter thereby locks itself to the teeth *p* on arm *f*, and thus holds said arm in adjusted position.

I claim as my invention:

1. A compass or analogous instrument comprising a pair of legs having enlarged upper ends or heads which are pivotally connected together; and a clamping device for said legs embodying a presser piece having an edge cooperative with the adjacent edges of said heads, and an actuating member for the presser piece, the cooperating edges of said head and presser piece having complementary wedge-shaped surfaces for direct engagement with each other.

2. A compass or analogous instrument, comprising a pair of legs having enlarged upper ends or heads which are pivotally connected together; and a clamping device for said legs embodying a presser piece having an edge cooperative with the adjacent edges of said heads, and an actuating member for the presser piece, one of such cooperating edges forming a wedge-shaped groove, and the other edge forming a wedge-shaped projection to fit therein.

3. A compass or analogous instrument, comprising a pair of legs having enlarged upper ends or heads which are pivotally connected together; and a clamping device for said legs embodying a presser piece having a wedge-shaped edge for cooperation with the adjacent edges of the heads, and an actuating screw for forcing the presser piece toward said heads to engage their cooperating edges.

4. A compass or analogous instrument,

comprising a pair of legs having enlarged upper ends or heads which are pivotally connected together and the edges of which conjointly form a wedge-shaped groove; and a clamping device for said legs embodying a presser piece having a wedge-shaped edge adapted to enter said groove, and an actuating screw for the presser piece.

5. A compass or analogous instrument, comprising a pair of legs having enlarged upper ends or heads which are pivotally connected together and the edges of which conjointly form a V-shaped groove; and a clamping device for said legs embodying a presser piece having a V-shaped edge adapted to enter said groove, and means for forcing said presser piece towards said heads.

6. In a compass, the combination of a pair of pivotally-connected legs, one of which embodies two parts movable with respect to one another, one part having teeth on its upper end; and a fine adjustment device for said part comprising a plate pivoted to the other part and provided with a pair of bearings, and a micrometer screw, or worm journaled in said bearings and engaged with said teeth, the pivotal movements of said plate locking said screw in such engagement so as to hold the parts against relative displacement.

7. In a compass, the combination of a pair of pivotally-connected legs, one of which embodies two parts movable with respect to one another one part being pivoted centrally to the other part and having its upper end cut at an incline to form half-length worm teeth; and a fine adjustment device for said part comprising a micrometer screw or worm meshing with said teeth and mounted on the other part both for rotation and for endwise swinging movement so as to initially rock the first named part about its pivot and subsequently engage said worm teeth torsionally and thereby hold said parts against relative displacement.

Signed at Stuttgart, Wurttemberg, Germany this 13th day of October A. D. 1921.

HEINRICH PERROT.
